Horace T. Robbins
Inventor.

United States Patent Office.

HORACE T. ROBBINS, OF BOSTON, MASSACHUSETTS.

Letters Patent No. 99,950, dated February 15, 1870.

IMPROVEMENT IN UMBRELLAS.

The Schedule referred to in these Letters Patent and making part of the same.

To all whom it may concern:

Be it known that I, HORACE T. ROBBINS, of Boston, in the county of Suffolk, and State of Massachusetts, have invented a new and useful Improvement in Umbrella and Parasol-Frames; and I do hereby declare that the following is a full, clear, and exact description of the construction and operation of the same, reference being had to the annexed drawings making a part of this specification, in which—

Figure 1 is a side view of an umbrella-frame having my improvement applied to it.

Figure 2 is a side view of one of the ribs detached from the frame.

Figure 3 is a view of the same taken at right angles to that of fig. 2.

Figure 4 is a side view of the supports detached from the rib.

Figure 5 is an end view of the same.

Similar letters refer to like parts in the different drawings.

a is the handle.

b the runner.

c the notch-plate.

d the ribs.

e the stretchers.

f the rib-joint plate.

g the supports.

The nature of my invention consists in providing umbrella and parasol-frames with a device to prevent the breakage and annoyance arising from the ribs and stretchers interlapping and becoming tangled with each other in opening them, thereby greatly facilitating that operation.

I construct my improved umbrella and parasol-

frames in any of the usual forms; but in order to obviate the trouble arising from the ribs and stretchers interlapping and tangling in the operation of opening them, I apply to the ribs supports *g*, which rest against the stretchers, and thereby hold the ribs in such a position as to keep the joints where the stretchers are attached to the ribs slightly distended from the handle when the umbrella is closed.

The elasticity of the ribs and stretchers allows the cover to be wrapped around them as compactly as it would be without the supports, but as soon as the cover is unwound they resume their former position, ready to expand at the slightest upward pressure on the runner.

I usually connect these supports to the ribs by pressure just below the rib-joint plate in the same way as that is attached. They may, however, be made of the same piece with the rib-joint plate by extending the lower end of it sufficiently to rest against the stretchers, or they may be made substantially by bending out the stretchers near the top to lie back against the ribs, or they may be attached to the stretchers near the rib-joint plate, or they may be applied to the stretchers lower down and rest against the handle, or they may be applied to the upper part of the ribs and rest against the handle.

I claim, in combination with the ribs or stretchers of an umbrella-frame, the stops or supports *g*, substantially as and for the purpose specified.

HORACE T. ROBBINS.
